BED SERVICE SET

Theodore D. Crane, Council Bluffs, Iowa

Application May 19, 1943, Serial No. 487,572

3 Claims. (Cl. 4—112)

1

My invention relates to a bed pan.

An object of my invention is to provide a device which can be used without discomfort to a bed ridden patient and which eliminates the necessity of raising the medial portions of the torso of the patient off of the upper surfaces of a bed in order to insert the bed pan under the buttocks of the patient.

A further object of my invention is to provide a construction which can be placed in position more rapidly than the rigid device formerly employed for the same purpose.

A further object of my invention is to provide a flexible device which will readily conform to the contours of the buttocks and other portions of the patient in contact therewith.

A further object of my invention is to provide a device of this character which can be quickly and easily cleaned after use and which can be carried or supported in a substantially folded condition after use.

A further object of my invention is to provide a gate-way associated with the device which will be readily accommodated to the patient's anus and buttocks, and which will conform thereto without discomfort to the patient, and at the same time insuring that the rectal discharges are efficiently gathered, and will flow uniformly in an even manner into the bed pan.

A further object of my invention is to provide an extending tab portion positioned beneath the gate-way to prevent soiling of the bed adjacent the buttocks or anus of the patient.

A further object of my invention is to provide a base sheet usable in combination with the bed pan arrangement, or which can be employed separately.

With these and other objects in view, my invention consists in the construction, arrangement, and combination of the various parts of my device, whereby the objects contemplated are attained, as hereinafter more fully set forth, pointed out in my claims, and illustrated in the accompanying drawing, in which:

Figure 1 is a plan view of the associated bed pan, base sheet, and urinal.

Figure 2 is a sectional view taken substantially along the lines 2—2 of Figure 1.

Figure 3 is a sectional detail taken along the lines 3—3 of Figure 1.

Figure 4 is a slightly modified form of the arrangement.

I have used the character 10 (see Figure 2) to designate a base sheet of fairly thin rubber or similar flexible material which is substantially

2

rectangular in shape and includes an extending tab portion. The extending tab portion of the member 10 lies normally directly beneath the tab portion 11 of a further sheet 12 which sheet 12 is substantially the same size and shape as the sheet 10.

Merging integrally with the sheet 12 is a gate member comprising the vertical walls 13 (see Figures 1 and 3) which walls 13 extend into the further integral vertical wall portions 14 which are substantially arcuate in shape and which merge into the further arcuate end wall 15, all of such walls being of a fairly thin resilient material such as rubber. The walls 14 and 15 merge together with the sheet 12 by means of the curved concave portions 16. For stiffening the gate walls 13, I provide the integrally formed lips 17 and 18 into which are placed the thin spring metal members 19 including the arcuate portions 20 at 20, these members 19 serving the purpose of maintaining the relatively long gate-way in a fairly rigid condition, the portions at 17 being rounded to prevent chafing, etc.

The walls 13 (see Figure 3) extend downwardly into the curved arcuate portions 21 which portions 21 are adapted to conform substantially to the hip cheeks of the patient.

When used, the base sheet 10 is placed under the patient and the bed pan portion comprising the sheet 12, the gate walls 13, and the further walls 14 and 15 are placed under the patient over the base sheet with the gate walls 13 being placed adjacent the anus, and between the hip cheeks. This operation can be performed without raising the patient, and by merely sliding the device into position under and between the legs, after the knees are raised.

It will be readily seen that the discharge from the rectum thereby flows between the walls 13 and into the bed pan, and is thus thereby efficiently confined to flowing into the bed pan in a uniform manner. The extending tab 11 also serves to keep the bedding clean at this portion and the other extending portions of the arrangement will similarly protect areas adjacent thereto.

It will also be noted that the arrangement by being resilient and soft will not cause the patient to roll to one side which would cause soiling of the bed clothing, and furthermore it will be noted that the arrangement provides comfort to the patient due to the resiliency of the parts. After use the sheet 12 can be folded together since it is flexible, whereby the arrangement can be carried away and cleansed by use of a brush, etc.

the curved portions at 16 providing easy access around the inner walls.

In some cases for extremely light discharges, or to rest the patient temporarily without soiling the bed clothes while the other portions are cleaned, the base sheet 10 can be employed alone without the other parts, or when the patient is being cleaned after discharge.

A slight modification of the arrangement is shown in Figure 4 wherein the gate-way is not necessarily stiffened and comprises a pan having slightly arcuate rubber vertical walls 21 which merge with the further walls 23 which walls 23 continue somewhat similarly to the walls 14 and 15 and with the walls 21 and 23 being integral with a flat sheet 29 including the extending tab 30. In this form of structure it will be noted that the members 21 will conform to the hip cheeks 31 of the patient which are shown in dotted lines, and will provide a gate-way at 32 which communicates to the anal portions 33.

It will now be seen that I have provided a bed service set which includes all of the advantages mentioned in the objects of my invention, in that it is comfortable in use, prevents soiling, is efficient in operation, and includes other advantages readily apparent.

Some changes may be made in the construction and arrangement of the parts of my invention without departing from the real spirit and purpose of my invention, and it is my intention to cover by my claims any modified forms of structure or use of mechanical equivalents which

may be reasonably included within their scope. I claim as my invention:

1. A bed service set comprising a flat thin base member, an excretion receiving member adapted to be positioned on said flat thin member, said excretion receiving member including vertically positioned side walls including a forward gateway for receiving rectal discharges, said vertical walls being of soft resilient material, said gateway being of resilient material, means for stiffening said gateway to provide relative rigidity thereto, including a pair of flat spring members attached to the gateway.

15 2. A bed service set comprising a flat thin base member; an excretion receiving member adapted to be positioned on said flat thin member, said excretion receiving member including vertically positioned side walls including a forward gateway for receiving rectal discharges, said vertical walls being of soft resilient material, said gateway being of a resilient material, means for stiffening said gateway to provide relative rigidity thereto, the outer side of said gateway including arcuate portions for conforming to the curvature 20 of a patient's hip cheeks.

25 3. A bed service set comprising an excretion receiving member, said excretion receiving member including vertically positioned side walls including a forward gateway for receiving rectal discharges, said gateway including a portion 30 adapted to engage a patient's hip cheeks.

THEODORE D. CRANE.
